MANUFACTURE OF MOTOR FUEL

Halsted Rogers Warrick, Teaneck, N. J., assignor
to The Texas Company, New York, N. Y., a cor-
poration of Delaware

Application December 22, 1943, Serial No. 515,215

6 Claims. (Cl. 260—683.4)

This invention relates to the manufacture of motor fuel and particularly to its manufacture from normally gaseous saturated hydrocarbons.

The present application is a continuation-in-part of my application Serial No. 326,593 filed March 29, 1940.

The invention broadly contemplates conversion of normally gaseous saturated hydrocarbons such as ethane and propane to motor fuel hydrocarbons of high anti-knock value by a process involving thermal conversion of the saturated hydrocarbons to form a synthetic hydrocarbon mixture containing unsaturated hydrocarbons including ethylene and higher molecular weight olefins. The synthetic mixture is subjected to polymerization such that the higher molecular weight olefins are converted to polymer gasoline leaving a hydrocarbon fraction consisting essentially of ethylene. The ethylene is then subjected to alkylation with isobutane.

More specifically, the invention involves thermal conversion of ethane, propane, normal butane or a hydrocarbon mixture containing these hydrocarbons at elevated temperature to form a synthetic mixture containing ethylene and higher molecular weight olefin hydrocarbons as well as converted hydrocarbons boiling within the range suitable for motor fuel. This mixture is treated to remove the normally liquid polymer gasoline hydrocarbons and to segregate a normally gaseous hydrocarbon fraction containing ethylene and higher molecular weight olefins such as propylene and butylene. This segregated fraction is subjected to catalytic polymerization so as to convert substantially all of the propylene and butylene to polymer gasoline hydrocarbons. The unconverted material comprising ethylene substantially free from propylene and butylene is then subjected to alkylation with isobutane in the presence of a suitable alkylation catalyst.

The alkylation is advantageously effected by contact with an active metallic halide catalyst at relatively low temperatures as will be described in more detail.

An object of the invention is to obtain the maximum conversion of ethane and propane as well as normal butane into valuable gasoline hydrocarbons of high antiknock value. This involves the formation of a substantial amount of ethylene and therefore a further object of the invention involves the conversion of this ethylene into high antiknock hydrocarbons suitable for aviation motor fuel.

It has been known heretofore to subject hydrocarbons such as propane to thermal conversion

to produce olefin hydrocarbons and polymer gasoline. Such conversion has involved the production of large amounts of ethylene which has been difficult to dispose of in an economic manner. It has now been found possible to effectively dispose of this ethylene by alkylation with isobutane in the presence of a metallic halide catalyst where the conditions of alkylation are carefully controlled as will be set forth later.

In order to describe the invention more fully, reference will now be made to the accompanying drawing illustrating one method of flow suitable for practicing the process of the invention.

As indicated in the drawing, a normally gaseous hydrocarbon charge comprising ethane, propane, butane or a mixture containing any of these hydrocarbons in substantial amount is conducted through a pipe 1. The charge is passed through a heater 2 wherein it is subjected to thermal conversion by heating to a temperature in the range of around 1000° to 1400° F. and under a pressure which may range from atmospheric to 500 lbs. per square inch gauge or higher. The temperature and pressure conditions to be used will depend on the nature of the charge and also on the relative amounts of liquid hydrocarbons, propylene and ethylene desired during the pyrolysis step. As a rule, extremely higher pressure favors liquid product formation at the expense of propylene and ethylene. On the other hand, lower pressure favors the production of normally gaseous olefins. The time of exposure to the elevated temperature may range from about 1 to 100 seconds for the production of ethylene or for maximum olefin production.

As a result of the thermal conversion treatment, the conversion mixture may contain around 10% to 25% by volume of ethylene. In addition, this mixture will contain hydrogen, methane, propane, propylene, normal and iso butanes and butylenes, as well as higher molecular weight hydrocarbons boiling up to about 500° F.

This synthetic mixture is passed from the heater 2 to an absorption tower 3 wherein it is subjected to scrubbing with a stream of polymer gasoline hydrocarbons drawn off from a subsequent point in the process and which scrubbing medium is introduced to the absorption tower through a pipe 4.

The liquid fraction collecting in the bottom of the absorption tower 3 is withdrawn through a pipe 5 and will comprise polymer gasoline hydrocarbons including some C₄ hydrocarbons. It is desirable to operate the absorption tower so that the unabsorbed hydrocarbons will not include C₅

hydrocarbons, at least to any substantial extent. This mixture containing absorbed hydrocarbons, mainly C₅ and heavier, is passed to a stabilizer 6 wherein it is stabilized by vaporizing the desired amount of low boiling hydrocarbons. The stabilized polymer gasoline is drawn off from the system through a pipe 7 and will comprise gasoline having an antiknock value of around 80 to 85 (CFRM).

The low boiling hydrocarbons vaporized in the stabilizer 6 are removed through a pipe 8 and may be recycled all or in part through a branch pipe 9 to the heater 2. If desired, these vaporized hydrocarbons may be passed all or in part through a pipe 10 communicating with a pipe 11, leading to a catalytic polymerization unit 12 to which reference will be made.

The normally gaseous hydrocarbons accumulating in the upper portion of the absorber 3 and which comprise ethylene, some propylene and butylene, as well as more volatile materials, are passed to a fractionator 13. The purpose of the fractionator 13 is to remove gaseous constituents such as hydrogen and methane which are drawn off through a pipe 14 and which may be disposed of as refinery fuel or in some other manner as may be desired. The fractionator 13 is operated under conditions of temperature and pressure necessary in order to remove the hydrogen and methane from the ethylene and other hydrocarbon constituents present in the mixture entering the fractionator 13.

The ethylene and other hydrocarbons, including propylene and butylene are drawn off through a pipe 15, communicating with the previously mentioned pipe 11 leading to the catalytic polymer unit 12.

In the catalytic polymer unit the hydrocarbons are subjected to contact with a polymerization catalyst such as phosphoric acid at a temperature of around 400° F. so that at least the bulk of the olefins of higher molecular weight than ethylene are converted to polymer gasoline hydrocarbons. Advantageously the polymerization is conducted so that the unconverted hydrocarbons issuing from the polymer unit will contain propylene and butylene in amount substantially less than 20%, and preferably not in excess of about 10%, by weight of the ethylene present. For example, the propylene and butylene content will be about 1% to about 5% of the ethylene, and may be as high as about 5 to 10%.

One purpose of the polymerization step is to reduce the quantity of olefins of higher molecular weight than ethylene so that the ethylene can be subjected to alkylation in an effective manner. Thus, it has been found that the presence of excess propylene and butylene causes considerable difficulty in the subsequent alkylation of ethylene with aluminum chloride as an alkylation catalyst since these higher molecular weight olefins cause rapid deterioration of the catalyst.

In the alkylation of ethylene with isobutane so as to produce an alkylate having a large content of 2,3 dimethylbutane, the presence of more than 10% of these higher molecular weight olefins in the ethylene feed to the alkylation reaction is undesirable. The presence of more than 10% of these higher molecular weight olefins materially reduces the yield of 2,3 dimethylbutane and results in an alkylate of lower octane value. The amount of ethylene reacted is reduced, and, in addition, catalyst consumption is materially increased by the presence of propylene and higher olefins.

While the total absence of propylene and higher olefins favors realizing the maximum yield of 2,3 dimethylbutane, nevertheless it is desirable to retain in the ethylene feed to the alkylation reaction a small amount of the higher olefins, namely about 1 to 10% by weight of the ethylene. The presence of this small amount of higher olefin is effective in preventing reduction in the fluidity of the complex catalyst during continued use in continuous operations.

The hydrocarbons are passed from the catalytic polymer unit 12 through a pipe 16 leading to a fractionator 17. The fractionator 17 is operated under conditions of temperature and pressure such that the liquid hydrocarbons are condensed and removed as a polymer gasoline from the bottom of the fractionator 17 through a pipe 18. This polymer gasoline may contain small amounts of normally gaseous hydrocarbons such as propane, for example. Therefore it is advantageously passed to the stabilizer 6 previously referred to wherein it is commingled with the polymer gasoline formed directly in the heater 2. If desired, a portion of it may be recycled through a pipe 19 communicating with the pipe 4 leading to the top of the absorber 3. In such case some of the normally gaseous constituents are volatilized in the absorber 3 and returned to the system through the fractionator 13 while the liquid hydrocarbon constituents are accumulated in the bottom of the absorber and drawn off through the pipe 5 to the stabilizer 6.

The gaseous hydrocarbons rich in ethylene discharged from the top of the fractionator 17 are passed through a pipe 20 to an alkylation unit 21 wherein the ethylene is subjected to alkylation with isobutane by contact with an active alkylation catalyst. The alkylated hydrocarbons are passed through a pipe 22 to a depropanizer 23 where normally gaseous constituents comprising mainly ethane and propane are separated from the higher boiling hydrocarbons. The depropanizer may comprise a fractionating tower or an absorption tower. Where it is operated as an absorption tower, the absorption medium may comprise straight-run gasoline with which it may be desired to blend the debutanized alkylated hydrocarbons. The absorption medium may also comprise a portion of the debutanized alkylate itself as will be explained later.

The ethane and propane separated from the alkylate in the depropanizer may be discharged all or in part through a pipe 24. However, it is advantageous to recycle these hydrocarbons to the heater 2. In such case, the recycled hydrocarbons are forced by a compressor 25 through a pipe 26 communicating with the heater inlet or with an intermediate point in the heating coil as indicated.

To effect conversion of ethane to ethylene, it is preferable to employ a high temperature, a low pressure, and a short time of exposure to the elevated temperature. For example, such conversion may be effected at a temperature of around 1300° to 1400° F. under a pressure of around 1 atmosphere and with a time of exposure of around 1 to 10 seconds. It is desirable, therefore, to pass the recycled ethane through that portion of the heating coil wherein approximately the foregoing conditions will prevail. If desired, a separate heater may be employed for the further conversion of these recycled hydrocarbons.

Referring again to the depropanizer 23, the alkylated hydrocarbon mixture from which the ethane and propane have been removed is drawn

off through a pipe 27 leading to a fractionator 28 wherein the alkylated mixture is debutanized to remove isobutane which is recycled through a pipe 29 to the alkylation unit 21 along with such additional isobutane as may be required for the reaction.

Debutanized alkylate is drawn off through a pipe 30 and comprises gasoline having an anti-knock value of 90 or above and suitable for aviation fuel. As already indicated, a portion of this 10 may be returned through a pipe 31 to the depropanizer 23 to serve as an absorption medium.

The alkylation of ethylene with isobutane is advantageously effected in a manner similar to that described in copending application Serial No. 327,575. As there described, the catalyst comprises a metallic halide such as aluminum chloride or aluminum bromide dispersed in a fluid body of preformed metallic halide-hydrocarbon complex. Thus, the reaction vessel is maintained substantially filled with a body of the fluid complex in which is suspended solid pulverulent aluminum chloride. The mixture is subjected to continuous agitation while the ethylene feed is continuously passed through the agitated mass together with an excess of isobutane, employing a pressure in the reaction zone of around 125 to 250 pounds per square inch gauge.

It is desirable to maintain the isobutane in substantial molecular excess over the ethylene undergoing treatment. For example, the ethylene and isobutane are passed through the catalyst mass in the proportion of about 1 part of ethylene to from 3 to 5 parts of isobutane, although even higher proportions of isobutane may be used, as for example 20 parts per part of ethylene. A reaction temperature of around 100° to 130° F. is maintained.

The preformed complex may comprise complex metallic halide-hydrocarbon compounds such as produced in a conventional alkylation reaction wherein a catalyst such as aluminum chloride has been employed with the resultant production of complex compounds. The complex material may be such as produced in the isomerization of normal paraffin hydrocarbons during contact with anhydrous metallic halides.

A suitable complex material may also be prepared directly by reacting aluminum chloride or other active metallic halide with paraffin or olefin hydrocarbons and particularly with olefin hydrocarbons having from 3 to 4 carbon atoms per molecule. It may also be prepared by reacting the metallic halide with alkyl halide such as propyl and butyl chlorides.

In using the alkylation catalyst, a small amount of hydrogen chloride or other hydrogen halide may be introduced along with the feed hydrocarbons in order to promote the reaction.

While specific temperatures and pressures as well as other conditions of operation have been described above for each step in the process, it is, of course, contemplated that the conditions of operation may vary somewhat from these as desired without departing from the scope of the 60 invention.

While removal of the excess propylene and higher olefins from the ethylene feed to the alkylation reaction by selective polymerization has been described, nevertheless it is contemplated that removal of these excess olefins, without conversion of the ethylene, also may be accomplished by other types of treatment such as by absorption in sulfuric acid; for example, the excess propylene and higher olefins may be absorbed in sulfuric 75 acid

acid of about 80 to 90% H₂SO₄, and preferably acid of about 84% H₂SO₄. The absorption with such acid may be carried out at a temperature of about 70 to 125° F. so that a residual ethylene fraction is obtained which contains from about 1 to 10% by weight of higher olefins.

Obviously many modifications and variations of the invention, as hereinbefore set forth, may be made without departing from the spirit and scope thereof and therefore only such limitations should be imposed as are indicated in the appended claims.

I claim:

1. A continuous process for manufacturing motor fuel hydrocarbons from normally gaseous saturated hydrocarbons which comprises subjecting the saturated hydrocarbons to conversion to produce a synthetic hydrocarbon mixture containing ethylene, higher molecular weight olefins and some normally gaseous saturated hydrocarbons, passing a stream of said mixture through a reaction zone wherein higher molecular weight olefins than ethylene are substantially entirely converted to polymer gasoline, removing the polymer gasoline hydrocarbons thereby leaving a residual ethylene fraction containing some normally gaseous saturated hydrocarbons and from about 1 to 5% of higher molecular weight olefins by weight of the ethylene, passing a stream of said residual ethylene fraction through an alkylation reaction zone containing a fluid alkylation catalyst comprising aluminum halide-hydrocarbon complex maintained under alkylation conditions at a temperature in the range of 100 to 130° F., 20 passing isobutane to said alkylation reaction zone in the proportion of from 3 to 5 parts isobutane to about 1 part ethylene, effecting reaction between isobutane and ethylene in said alkylation zone in the presence of a small amount of hydrogen halide to form saturated hydrocarbons of high antiknock value, withdrawing the resulting alkylated hydrocarbons and unreacted normally gaseous saturated hydrocarbons, and returning said normally gaseous saturated hydrocarbons to 30 the thermal conversion reaction.

2. The method according to claim 1 in which the alkylation catalyst is a fluid aluminum chloride-hydrocarbon complex.

3. A continuous process for manufacturing motor fuel hydrocarbons from normally gaseous saturated hydrocarbons which comprises subjecting the saturated hydrocarbons to conversion to produce a synthetic hydrocarbon mixture containing ethylene, higher molecular weight olefins and some normally gaseous saturated hydrocarbons, passing a stream of said mixture to a treating zone, effecting therein conversion of higher molecular weight olefins to normally liquid products without substantial conversion of ethylene, removing said normally liquid products thereby leaving a residual ethylene fraction containing some normally gaseous saturated hydrocarbons and from about 1 to 5% of higher molecular weight olefins by weight of the ethylene, passing a stream of said residual ethylene fraction through an alkylation reaction zone containing a fluid alkylation catalyst comprising aluminum halide-hydrocarbon complex maintained under alkylation conditions at a temperature in the range of 100 to 130° F., 50 passing isobutane to said alkylation reaction zone in the proportion of from 3 to 20 parts isobutane to about 1 part ethylene, effecting reaction between isobutane and ethylene in said alkylation zone in the presence of a small amount of hydrogen halide to form saturated hy-

drocarbons of high antiknock value, withdrawing the resulting alkylated hydrocarbons and unreacted normally gaseous saturated hydrocarbons, and returning said normally gaseous saturated hydrocarbons to the thermal conversion reaction.

4. A continuous process for manufacturing motor fuel hydrocarbons from normally gaseous saturated hydrocarbons which comprises subjecting the saturated hydrocarbons to conversion to produce a synthetic hydrocarbon mixture containing ethylene, higher molecular weight olefins and some normally gaseous saturated hydrocarbons, passing a stream of said mixture through a reaction zone wherein higher molecular weight olefins than ethylene are substantially converted to polymer gasoline without substantial conversion of ethylene, removing the polymer gasoline hydrocarbons thereby leaving a residual ethylene fraction containing some normally gaseous saturated hydrocarbons and from about 1 to 10% of higher molecular weight olefins by weight of the ethylene, passing a stream of said residual ethylene fraction through an alkylation reaction zone containing a fluid alkylation catalyst comprising aluminum halide-hydrocarbon complex maintained under alkylation conditions at a temperature in the range of 100 to 130° F., passing isobutane to said alkylation reaction zone in an amount sufficient to maintain a substantial molecular excess of isobutane over ethylene undergoing treatment therein, effecting reaction between isobutane and ethylene in said alkylation zone in the presence of a small amount of hydrogen halide to form saturated hydrocarbons of high antiknock value, withdrawing the resulting alkylated hydrocarbons and unreacted normally gaseous saturated hydrocarbons, and returning said normally gaseous saturated hydrocarbons to the thermal conversion reaction.

5. A continuous process for manufacturing motor fuel hydrocarbons from normally gaseous saturated hydrocarbons which comprises subjecting the saturated hydrocarbons to conversion to produce a synthetic hydrocarbon mixture containing ethylene, higher molecular weight olefins and some normally gaseous saturated hydrocarbons, passing a stream of said mixture to a treating zone, effecting therein conversion of higher molecular weight olefins to normally liquid products without substantial conversion of ethylene, removing said normally liquid products thereby leaving a residual ethylene fraction containing some normally gaseous saturated hydrocarbons and

from about 1 to 10% of higher molecular weight olefins by weight of the ethylene, passing a stream of said residual ethylene fraction through an alkylation reaction zone containing a fluid alkylation catalyst comprising aluminum halide-hydrocarbon complex maintained under alkylation conditions at a temperature in the range of 100 to 130° F., passing isobutane to said alkylation reaction zone in an amount sufficient to maintain a substantial molecular excess of isobutane over the ethylene undergoing treatment therein, effecting reaction between isobutane and ethylene in said alkylation zone in the presence of a small amount of hydrogen halide to form saturated hydrocarbons of high antiknock value, withdrawing the resulting alkylated hydrocarbons and unreacted normally gaseous saturated hydrocarbons, and returning said normally gaseous saturated hydrocarbons to the thermal conversion reaction.

6. A continuous process for manufacturing motor fuel hydrocarbons from normally gaseous saturated hydrocarbons which comprises subjecting the saturated hydrocarbons to conversion to produce a synthetic hydrocarbon mixture containing ethylene, higher molecular weight olefins and some normally gaseous saturated hydrocarbons, passing a stream of said mixture to a treating zone, effecting therein conversion of higher molecular weight olefins to normally liquid products without substantial conversion of ethylene, removing said normally liquid products thereby leaving a residual ethylene fraction containing some normally gaseous saturated hydrocarbons and from about 5 to 10% of higher molecular weight olefins by weight of the ethylene, passing a stream of said residual ethylene fraction through an alkylation reaction zone containing a fluid alkylation catalyst comprising aluminum halide-hydrocarbon complex maintained under alkylation conditions at a temperature in the range of 100 to 130° F., passing isobutane to said alkylation reaction zone in the proportion of from 3 to 20 parts isobutane to about 1 part ethylene, effecting reaction between isobutane and ethylene in said alkylation zone in the presence of a small amount of hydrogen halide to form saturated hydrocarbons of high antiknock value, withdrawing the resulting alkylated hydrocarbons and unreacted normally gaseous saturated hydrocarbons, and returning said normally gaseous saturated hydrocarbons to the thermal conversion reaction.

HALSTED ROGERS WARRICK.
